UNITED STATES PATENT OFFICE.

THOMAS A. COLEMAN, OF PORTLAND, OREGON.

SAWMILL.

Application filed July 22, 1926. Serial No. 124,188.

This invention relates to improvements in sawmills, and more particularly to the system or means for operating the log turners and niggers.

5 One of the objects of the present invention is to provide an improved system of the character referred to wherein a single control lever is provided for operating both the log turners and niggers, and wherein means are 10 provided for selectively connecting the control lever to the latter.

Another object is to provide an improved system of the character referred to wherein a single control lever is provided for both 15 the log turners and niggers and which has all the advantages, as regards ease and rapidity of operation, of such systems constructed heretofore wherein separate control levers are used for the log turners and niggers.

20 Other objects and advantages will herein after appear.

For the purpose of illustrating the invention, one embodiment thereof is shown in the drawings, in which

25 Figure 1 is a diagrammatic plan view of the improved system, partly in section, some of the parts being removed for the sake of clearness;

Fig. 2 is an enlarged sectional view, taken 30 on the line 2-2 in Fig. 3;

Fig. 3 is a front elevational view of Fig. 1;

Fig. 4 is a side elevational view, looking toward the left in Fig. 1;

Fig. 5 is an enlarged view, similar to Fig. 35 4 and taken therefrom, some of the parts being broken away and shown in section for the sake of clearness;

Fig. 6 is an end elevational view, looking toward the left in Figs. 4 and 5; and

40 Fig. 7 is a sectional view, taken on the line 7-7 in Fig. 5.

In Figs. 1, 3 and 4 are shown, in a general way, the usual cylinders 10 and 11 for the niggers, and the log turner which includes the 45 push arm cylinder 12 and the hook arm cylinder 13, cylinder 12 being provided with an operating valve 14 enclosed in a valve chest 15, and cylinder 13 being provided with a similar operating valve enclosed in a valve 50 chest 16. The operating valves for cylinders 12 and 13 are of well known construction and operate to admit fluid under pressure to either side of the pistons working in these cylinders and to simultaneously provide an exhaust 55 passage for the other sides of these pistons. The nigger cylinders are also provided with

the usual operating valves to which are connected the stems 17 and 18, respectively, reciprocal movement of the latter causing operation of the nigger valves to cause upward or downward movement of the pistons operating in cylinders 10 and 11. The construction just described is well known and has only been shown in sufficient detail to enable those skilled in the art to understand the 60 manner in which the operating valves for the log turner and nigger cylinders are connected up in the improved operating system therefor.

A rod 19 is supported in suitable bearings 70 20 and is provided at one end with an arm 21 fixed thereto and connected to the valve stem 22 for the operating valve of cylinder 13 through the rod 23 and the lever 24 pivotally supported at 25. An operating arm 26 is fixed 75 on the other end of rod 19 so that upon rotary movement of this arm in opposite directions about the axis of rod 19 the valve for cylinder 13 is operated to cause inward or outward movement of the piston working therein. 80

For the purpose of moving the operating valve 14 for cylinder 12, a section of pipe 27 is loosely mounted on rod 19 between the bearing 20 and the bearing at the right end of rod 19, and an arm 28 fixed to one end of 85 this pipe section and connected to the stem 29 for valve 14 through the rod 29' and the lever 30 pivotally supported at 31, an operating arm 32 being fixed to the other end of this pipe section whereby arm 32 is operable 90 upon rotary movement thereof in either direction about the common axis of rod 19 and pipe section 27 to effect movement of the operating valve 14 in either direction, the loose fit between rod 19 and pipe section 27 95 permitting of independent rotary movement of these parts by means of their respective operating arms 26 and 32, whereby the operating valves for cylinders 12 and 13 are independently operable. 100

The operating valve for the nigger cylinder 11 is actuated in either direction by means of an arm 33 connected to the valve stem 18 and fixed on one end of a second pipe section 34 loosely fitted on rod 19 between 105 the intermediate bearing 20 and the bearing at the left end of the rod, an operating arm 35 being fixed on the other end of the pipe section 34. The operating valve for the nigger cylinder 10 is actuated by an arm 36 connected to the valve stem 17 and fixed on a short 110 rod section 37 arranged in alignment with

rod 19 and supported by suitable bearings 38, an operating arm 39 being fixed, as shown, on the right end of rod 37.

From the foregoing it will be seen that the 5 operating arms 26 and 32 for the log turner cylinders 12 and 13 and the operating arms 35 and 39 for the nigger cylinders 10 and 11 are supported for pivotal movement about a common axis and are independently movable 10 with respect to each other about this axis whereby the respective pistons working in these cylinders may be caused to move in any desired direction and independently of each other.

15 As more clearly shown in Fig. 5, the operating arms 26 and 32 for the log turner are provided at their respective ends with pins 40 and 41 fixed therein and extending therethrough beyond each side thereof, while the 20 operating arms 35 and 39 for the nigger cylinders are provided at their respective ends with similar pins 42 and 43 also fixed in these ends and extending therethrough beyond opposite sides of the same, the pins being in 25 alignment and parallel to rods 19 and 37, and the respective adjacent ends of pins 40 and 43 and those of pins 41 and 42 abutting for the purpose hereinafter explained.

The means for causing rotary movement 30 of the operating arms 26, 32, 35 and 39, for the purpose explained above, includes a manually-operable control lever 44 common thereto and which is supported on a gimbal joint which may be of any well known construction and which is indicated generally by the reference numeral 45, this joint permitting of universal pivotal movement of lever 44. A shift bar 46 is connected through a rod 47 to the lower end of lever 44, the latter 35 being pivotally connected to the adjacent end of rod 47 by means of a suitable coupling 48. The other end of shift bar 46 extends between the ends of operating arms 32 and 35 and is provided with an opening loosely receiving one or the other of the adjacent 40 ends of pins 41 and 42, this end of shift bar 46 being laterally movable between arms 32 and 35 whereby the bar may be shifted laterally into interlocking engagement with one 45 or the other of the adjacent ends of pins 41 and 42, as more clearly shown in Fig. 5.

A second shift bar 49 is connected through the rod 50 to one arm of a bell crank 51 pivotally supported at 52, the other arm of the 55 bell crank being connected to the lower end of control lever 44 by means of the rod 53 and suitable coupling members 54 and 55. The free end of shift bar 49 is arranged between the upper ends of operating arms 26 and 39 60 for lateral movement from one to the other, and is provided with an opening, as more clearly shown in Fig. 5, for loosely receiving the adjacent ends of pins 40 and 43 whereby bar 49 may be interlocked with one or the 65 other of the latter. The adjacent ends of pins

40 and 43, as well as those of pins 41 and 42, abut so that the respective shift bars cooperating with these pins are at all times supported by one or the other and are readily shiftable from one pin over upon the adjacent 70 end of the other.

In the drawings the shift bars 46 and 49 are shown as being interlocked with the pins 40 and 41 fixed in the ends of the operating arms 26 and 32, respectively, for the log 75 turner cylinders 12 and 13, this arrangement providing for an operating connection between the control lever 44 and arm 32 through shift bar 46 and rod 47, as well as an operating connection between the control lever and 80 arm 26 through shift bar 49, rod 50, bell crank 51 and rod 53. Referring more particularly to Fig. 1, it will be seen from the foregoing that upon backward and forward movement of control lever 44 in a vertical plane transverse to rod 19, the operating arm 32 will be 85 made to rotate in the desired manner about the axis of rod 19 to actuate the operating valve 14, of cylinder 12, and that this movement will cause no movement of shift bar 49. On the other hand, it will be seen that upon backward and forward movement of control lever 44 in a vertical plane parallel to rod 19, shift bar 49 will be caused 90 to move backward and forward in the desired manner to effect rotary movement of operating arm 26 to actuate the valve for the log turner cylinder 13, and that this movement of lever 44 in this plane will cause no movement of shift bar 46. By moving control lever 44 in one or the other of these planes, it is therefore possible to operate one 95 or the other of the log turner cylinders 12 and 13. When it is desired to operate both cylinders 12 and 13, the control lever 44 is given 100 a circular movement in such manner as to simultaneously pull in or push out on both of the rods 47 and 53, or to pull in on one of these rods and simultaneously push out on the other to thereby cause simultaneous forward or backward movement of both of the pistons working in cylinders 12 and 13 or 105 forward movement of one piston and simultaneous backward movement of the other, this operation of these pistons being entirely in 110 the discretion of the operator and depending upon the way in which it is desired to handle the log. It will be understood that during this operation of the log turner cylinders, there is no operation of the nigger cylinders 120 10 and 11 for the reason that the shift bars 46 and 49 are entirely disengaged from pins 42 and 43 fixed in the operating arms 35 and 39, respectively, for the nigger cylinders.

When it is desired to operate the nigger 125 cylinders 10 and 11, the shift bars 46 and 49 are moved laterally from pins 41 and 40 into interlocking engagement with pins 42 and 43 whereby the valve operating mechanism for the nigger cylinders is operatively connected 130

to the common control lever 44 and the valve operating mechanism for the log turner cylinders 12 and 13 simultaneously disconnected from lever 44. The control lever 44 may 5 now be moved in the same manner explained above in connection with the log turner cylinders 12 and 13, whereby one or the other of operating arms 35 and 39 may be rotated back and forth about the axis of rod 19, or 10 both of these arms simultaneously rotated forward and backward, or one arm rotated forward and the other arm simultaneously rotated backward, this movement of the operating arms causing movement of one or 15 the other of the pistons in the nigger cylinders, simultaneous upward or downward movement of both of these pistons, or upward movement of one piston and simultaneous downward movement of the other, thus providing 20 for complete flexibility of operation of the niggers to handle the log in any manner desired.

This means for simultaneously moving the shift bars 46 and 49 laterally between the 25 pair of operating arms 32 and 35 and the pair of operating arms 26 and 39 to simultaneously connect and disconnect the log turner cylinders 12 and 13 and the nigger cylinders 10 and 11 to and from the common control 30 lever 44 therefor, will now be described. A bar 56 is supported in suitable bearings 57 and 58 for axial shifting movement, the end 35 of this bar being square and bearing 58 supporting the latter being provided with a square opening to loosely receive the same, as more clearly shown in Fig. 6, whereby bar 56 is held against rotary movement. A collar 60 is fixed on bar 56 and provided with depending spaced lugs 61 loosely embracing shift bar 46 to cause lateral movement thereof upon axial movement of bar 56 while permitting of free backward and forward movement of the shift bar 46 under the action of control lever 44. A similar collar 62 is fixed 40 on bar 56 and provided with depending spaced lugs 63 extending on either side of shift bar 49 whereby the latter is also caused to move laterally upon axial movement of bar 56.

For the purpose of locking the valve operating mechanism for the niggers against movement when the valve operating mechanism for the log turner cylinders 12 and 13 is connected to control lever 44, a depending 45 arm 64 is fixed on bar 56 adjacent the nigger operating arm 35 and is provided with an opening for receiving the outer end of pin 42. A similar depending arm 65 is fixed on bar 56 adjacent the other nigger operating arm 39 and is provided at its end with an opening for receiving the outer end of pin 43. The arrangement of collars 60 and 62 and arms 64 and 65 is such that upon shifting 50 of bar 56 to its extreme position to the right, as viewed in Fig. 5, shift bars 46 and 49 will

be moved laterally into connecting engagement with the log turner operating arms 26 and 32 and the fixed arms 64 and 65 simultaneously moved into locking engagement of the pins 42 and 43, respectively, whereby the 55 valve operating mechanism for the nigger cylinders 10 and 11 is locked against movement. A depending arm 66 is fixed on bar 56 adjacent the log turner operating arm 32 and is provided at its end with an opening 60 for receiving the outer end of pin 41, a similar depending arm 67 being fixed on bar 56 adjacent the other log turner operating arm 26 and being provided at its end with an opening 65 for receiving the outer end of pin 40. Upon shifting of bar 56 to its extreme position to the left, the depending lugs 61 and 63 will cause simultaneous lateral movement of shift bars 46 and 49 from pins 40 and 41 to pins 42 and 43, respectively. This 70 movement of bar 56 will also cause movement of arms 64 and 65 to the left out of locking engagement with pins 42 and 43 and simultaneous movement of arms 66 and 67 to the left into locking engagement with pins 41 and 40, respectively. In this position of bar 56, therefore, the valve operating mechanism for the nigger cylinders 10 and 11 is 75 connected to the common control lever 44 and the valve operating mechanism for the log turner cylinders 12 and 13 locked against movement.

A member 68 provided with depending legs 69 straddling bar 56 is arranged loosely between collars 70 fixed on the latter and is pivotally connected at 71 to a suitable fixed base 72, a weight 73 being fixed to the upper end of member 68 for the purpose hereinafter explained. Member 68 is connected through a rod 74, a bell crank 75 pivotally supported 80 at 76, and a rod 77 to the depending arm 78 of a T-shaped plate 79 pivotally supported at 80. Rods 81 and 82 are pivotally connected to plate 79, as more clearly shown in Fig. 3, and extend upwardly through a plate 83 fixed 85 to the floor. From the foregoing it will be seen that when the operator presses his foot upon the upper end of rod 81 and moves the same downwardly, bar 56 will be shifted axially to its extreme position to the left, as 90 viewed in Fig. 5, and that when the operator pushes down on the upper end of rod 82 the bar 56 is shifted axially to its extreme position to the right. When bar 56 is intermediate its extreme positions, the center of gravity 95 of weight 73 is over the pivot point 71 so that the weight falls to either side of this pivot point and acts to yieldingly hold bar 56 in one or the other of its extreme positions.

For the purpose of accommodating different operators, the controlling movements of lever 44 explained above may be made to have a different effect on the respective valve operating mechanisms for the log turner and nigger cylinders by reversing the positions of 100

arms 21 and 28, as shown in dotted lines in Fig. 4, and reversing the position of bell crank 51, as indicated in Fig. 1, the connecting rod 53 being extended in any suitable manner to 5 permit of its being connected at this time to the bell crank by means of coupling 54. By making either one or both of these changes, it will be seen that any desired effect may be had, depending upon the particular operator 10 and the manner in which he is accustomed to work the control lever 44.

From the foregoing it will be seen that an improved system has been provided for controlling the log turner cylinders and the nigger cylinders wherein a common control lever 44 is provided for the latter and wherein means are provided for selectively connecting the common control lever to the valve operating mechanism for either the log turner 20 cylinders or the nigger cylinders.

One embodiment of the invention has been shown and described, but of course various changes may be made such as in the size, shape and arrangement of the parts without departing from the spirit of the invention or the scope of the claims.

The invention claimed is:

1. In a sawmill, a log turner, a nigger, a single controlling member therefor, and 30 means for selectively connecting or disconnecting said member to said log turner and nigger.

2. In a sawmill, a log turner, a nigger, operating means for said log turner, operating 35 means for said nigger, a controlling member common to said means, means operable to provide an operating connection between said member and one or the other of said operating means or to interrupt such connection.

40 3. In a sawmill, a log turner, a nigger, operating means for said log turner, operating means for said nigger, a controlling member common to said means, and means including a movably supported element operable upon 45 movement of said element to one position to provide an operating connection between said member and said nigger operating means and a disconnection between said member and said log turner operating means and operable upon movement of said element to a different position to provide an operating connection between said member and said log turner operating means and a disconnection 50 between said member and said nigger operating means, and means for effecting movement of said element to said positions.

4. In a sawmill, the combination with the log turner and nigger operating mechanisms thereof, of a single controlling member 60 therefor, and means interposed between said mechanisms and said member for operatively connecting or disconnecting the latter to one or the other of said mechanisms.

5. In a sawmill, the combination with the 65 log turner and nigger operating mechanisms

thereof, of a controlling member therefor, means connected to said member, said means being movable into operating engagement with one or the other of said mechanisms to provide an operative connection between 70 either of the latter and said member or to interrupt such connection, and means for effecting movement of said last-named means.

6. In a sawmill, a log turner, a nigger, operating means for said log turner, operating 75 means for said nigger, a controlling member common to said means, means operable to provide an operating connection between said member and either of said operating means and to disconnect and simultaneously hold 80 the other of said operating means against movement.

7. In a sawmill, the combination with the log turner and nigger, of a pair of operating arms connected to the latter, respectively, and 85 supported for rotary movement about a common axis, a manually-operable element common to said arms for actuating the same, means for providing an operating connection between said element and one or the other of 90 said arms, said means including a member connected to said element and supported adjacent said arms for shifting movement with respect thereto, means providing an operative connection between one of said 95 arms and said member upon shifting of the latter to a given position, means providing an operative connection between the other of said arms and said member upon shifting of the latter to a different position, and means 100 for shifting said member.

8. In a sawmill, the combination with the log turner and nigger, of a pair of operating arms connected to the latter respectively and supported for rotary movement about a common axis, a manually-operable element common to said arms for actuating the same, means for providing an operative connection between said element and one or the other of 105 said arms, said means including a member connected to said element and interposed between said arms and supported for movement from one to the other, aligned pins fixed in the respective ends of said arms, said member being provided with an opening for receiving either of the adjacent ends of said pins upon said movement of said member, and means for moving said member.

9. In a sawmill, the combination with the operating valves for the log turner and nigger cylinders, of a manually-operable member common to said valves for actuating the same, and means for selectively connecting or disconnecting said member to the log turner and nigger operating valves.

10. In a sawmill, the combination with the operating valves for the log turner and nigger cylinders, of a manually-operable member common to said valves for actuating the same, and means operable to connect said 110

- member to the log turner valves and to simultaneously lock the nigger valves against operation or to connect said member to the nigger valves and to simultaneously lock the log turner valves against operation.
11. In a sawmill, the combination with the respective valve operating mechanisms for the log turner and nigger cylinders, of a manually-operable member common to said mechanisms for actuating the same, a pair of elements connected to said member and supported for movement into and out of operative relation with said mechanisms respectively, and actuating means common to said elements for causing simultaneous movement thereof.
12. In a sawmill, the combination with the respective valve operating mechanisms for the log turner and nigger cylinders, of a manually-operable actuating member common to said mechanisms, a pair of elements connected to said member and supported for lateral shifting movement into and out of operative relation with said mechanisms respectively, an axially shiftable rod connected to said elements and movable in one direction to effect movement of the latter into operative relation with the log turner mechanism and out of operative relation with the nigger mechanism and movable in the opposite direction to effect movement of said elements into operative relation with the nigger mechanism and out of operative relation with the log turner mechanism.
13. In a sawmill, the combination with the respective valve operating mechanism for the log turner and nigger cylinders of a manually-operable actuating member common to said valves, a pair of elements connected to said member and supported for lateral shifting movement into and out of operative relation with said mechanisms respectively, an axially shiftable rod connected to said elements and movable in one direction to effect movement of the latter into operative relation with the log turner mechanism and out of operative relation with the nigger mechanism and movable in the opposite direction to effect movement of said elements into operative relation with the nigger mechanism and out of operative relation with the log turner mechanism, and a weighted member associated with said rod for holding the same in its respective positions of operation.
14. In a sawmill, the combination with the log turner cylinders and operating valves therefor and the nigger cylinders and operating valves therefor, of a pair of operating arms connected respectively to one of the log turner valves and one of the nigger valves, a second pair of operating arms connected respectively to the other log turner valve and the other nigger valve, a controlling member common to said arms, an element connected to said member and associated with said first pair of arms for movement into operative relation with one or the other, a second element connected to said member and associated with said second pair of arms for movement into operative relation with one or the other, and means for effecting movement of said elements in such wise as to provide an operative connection between said member and the log turner valves or between said member and the nigger valves.
15. In a sawmill, the combination with the log turner cylinders and operating valves therefor and the nigger cylinders and operating valves therefor, of a pair of operating arms connected respectively to one of the log turner valves and one of the nigger valves, a second pair of operating arms connected respectively to the other log turner valve and the other nigger valve, a controlling member common to said arms, an element connected to said member and associated with said first pair of arms for movement into operative relation with one or the other, a second element connected to said member and associated with said second pair of arms for movement into operative relation with one or the other, and means for effecting movement of said elements in such wise as to provide an operative connection between said member and the log turner valves or between said member and the nigger valves, and means for locking the disconnected valves against operation.
16. In a sawmill, the combination with the log turner cylinders and operating valves therefor and the nigger cylinders and operating valves therefor, of a pair of operating arms connected respectively to one of the log turner valves and one of the nigger valves, a second pair of operating arms connected respectively to the other log turner valve and the other nigger valve, a controlling member common to said arms, an element connected to said member and associated with said first pair of arms for movement into operative relation with one or the other, a second element connected to said member and associated with said second pair of arms for movement into operative relation with one or the other, means including an axially movable rod for effecting movement of said elements in such wise as to provide an operative connection between said member and the log turner valves upon movement of said rod in one direction and between said member and the nigger valves upon movement of said rod in the opposite direction, and means for effecting said movements of said rod.
17. In a sawmill, the combination with the log turner cylinders and operating valves therefor and the nigger cylinders and operating valves therefor, of a controlling member common to said valves, and means for selectively connecting or disconnecting said member to the log turner and nigger valves.

18. In a sawmill, a log turner, an operating arm therefor, a nigger, an operating arm for said nigger, said arms being supported for pivotal movement about a common axis and 5 provided at their respective ends with fixed pins extending therethrough and beyond opposite sides of said ends, said pins being arranged in alignment and in parallel spaced relation with respect to said axis, a controlling member common to said arms, an element connected at one end to said member, the other end of said element being laterally movable and extending between said arms and being provided with an opening for receiving one or the other of the adjacent ends 10 of said pins whereby said element is operable upon said lateral movement thereof to selec-

tively connect said member to said log turner and nigger, a rod arranged parallel to the axis of rotation of said arm, means for supporting said rod for axial movement and for holding the same against rotation, means fixed to said rod for effecting lateral movement of said element upon axial movement of said rod, means fixed to said rod and adapted 20 and arranged to interlock with either of said pins upon axial movement of said rod to effect lateral movement of said element into operative relation with the other of said pins, and means for causing axial movement of 25 said rod.

In witness whereof, I hereto affix my signature.

THOMAS A. COLEMAN.
